Christy M. Del Mas, New York, N. Y., assignor to Michael P. Grace, New York, N. Y.

Application May 11, 1953, Serial No. 24,949

Term of patent 14 years

(Cl. D9—2)

To all whom it may concern:

Be it known that I, Christy M. Del Mas, a citizen of the United States of America, residing at city, county, and State of New York, have invented a new, original, and ornamental Design for a Toothbrush, of which the following is a specification, reference being had to the accompanying drawing, forming part thereof.

The characteristic features of my design are shown by full lines in the drawing.

I claim:

The ornamental design for a toothbrush, as shown and described.

CHRISTY M. DEL MAS.
